UNITED STATES PATENT OFFICE.

GEORG MAX WEHNER, OF DRESDEN, GERMANY.

BAND-LOOM.

1,248,223.

Specification of Letters Patent. Patented Nov. 27, 1917.

Application filed August 21, 1913. Serial No. 785,883.

To all whom it may concern:

Be it known that I, GEORG MAX WEHNER, a subject of the German Empire, residing at Dresden, in the Kingdom of Saxony, Germany, have invented certain new and useful Improvements in Band-Looms, of which the following is a full and complete specification.

My invention relates to band looms which are adapted to weave endless bands. The object of my invention is to facilitate the removal of the endless band from the reed frame and breast beam of the loom, without stretching or tearing the band, and without being obliged to bodily remove the breast beam.

Heretofore, endless bands have been woven in various ways, as for instance, described in German Patent No. 205,740. In these cases, just before the band is completed, and when a regular feeding is impossible, the band is thrown out of the reed frame of the batten, and after having been completed, is removed from the loom. This is destructive to the woven product, which must be stretched to remove it from the reeds.

My invention consists in so constructing the loom that the upper part of the reed frame may be easily removed therefrom, and the reeds turned away and removed with the woven band.

Besides this, the woven band is led over one or more cylinders connected to the breast beam but easily detached therefrom.

In the accompanying drawings, Figure 1 is a sectional side view of the loom; Fig. 2 is a top view of the loom; and Figs. 3, 4 and 5 are detailed views of the reed frame on an enlarged scale, being respectively a front view, a top view, and a vertical cross-section thereof.

Similar reference numbers indicate corresponding parts throughout the several figures of the drawings.

Referring to the drawings, the band is led around three points of support, two of which are marked by numbers 1 and 2. The third point of support consists of the removable cylinders *b*, *c*, connected to the breast beam. The shafts of these cylinder *b* and *c* rest in the open bearings *d* fastened upon the breast beam. These bearings are open in a direction opposite to the pull of the band.

The band is stretched by any pulling means

similar to those disclosed in German Patent No. 205,740.

The reed frame is fastened to the batten *f* by the vertical bars *g* to which the horizontal members *h* are fastened. The shuttle 60 may be operated in these horizontal members *h* and the reeds are arranged between them. These reeds consist of dents *i* whose upper and lower ends are threaded on clamping rods *p*, *p'* having appropriate spacing means, so that all the reeds can be bodily moved together. The lower end of each reed *i*, as can be seen in Fig. 5, rests in a recess *j* in the batten *f*, and the reeds are held in position by the bolt *k*. The upper end 70 of the reed frame is composed of two spaced bolts *l*, *l*, which are connected by the screws *m* passing through the wooden bars *n* which act as spacing means.

The vertical bars of the frame extend between the spacing means *n*. There is a gap 75 in the upper spacing means *n* at the place where the reeds are located.

The upper part of the reed frame is loosely attached so that the screws *m* rest in 80 openings *o* between the vertical bars *g*.

The upper ends of the reeds project as can be seen from Figs. 3 and 5 between the bolts *l*, *l*.

If the bolt *K* is loosened and the upper 85 part of the reed frame is removed, as may be readily done, then each section of the reeds can be readily removed with the band, or can be turned in any desired direction. The rod *p'* is detachable.

After the bands have been woven in the loom until the shuttle can no longer be operated because the shed is so small the pulling means are gripped so that no pull is exerted, the cylinders *b* and *c* are detached from the 95 bearings and moved away sidewise and the batten *f* is detached from its depending supporting arm at one side of the loom and shifted toward the breast beam. The heddle frames are also opened on the same side so 100 that the woven bands can be removed (without disturbing the breast beam) to be completed by hand. The reeds and heddles can be moved together with the band as a unit.

I have shown one embodiment of my invention, but it is clear that changes may be made therein without departing from the spirit thereof.

I claim:

1. In a band loom a reed comb comprising 110

a plurality of dents having their upper and lower ends rigidly connected, so that these dents form a single rigid comb, means for detachably supporting the lower ends of these dents in the batten, and removable holding means for keeping the upper ends of these said dents in position, whereby when these removable holding means are removed, the said comb can be bodily lifted 10 away from the said batten, together with the band.

2. In a band loom a reed comb consisting of a plurality of dents having their upper and lower ends rigidly connected, so that these dents form a single rigid comb, means for detachably supporting the lower end of the said comb on the batten, and spaced removable bolts arranged on each side of the upper end of the said comb, whereby when 20 the said bolts are removed, the said comb can be bodily moved with respect to the said batten.

3. In a band loom, a breast beam, means for leading an endless band around the said breast beam, open bearings connected to the said breast beam, and a detachable roller having its ends rotatable in said open bearings, said bearings being open in a direction opposite to the pull of the said endless band,

whereby when the said roller is removed 30 from its said bearings, the said band can be removed without disturbing the breast beam.

4. In a band loom, a batten having a plurality of spaced vertical bars extending upwardly therefrom, reed combs arranged on said batten between these said vertical bars, and consisting of a plurality of dents, having their upper and lower ends rigidly connected, and having their lower ends detachably secured to said batten, and a removable cap loosely resting upon said vertical bars, said cap consisting of two spaced bolts, one arranged on each side of said vertical bars, the said reed combs extending into the space between the said bolts of the 45 said cap, whereby when the said cap is removed, the said combs can be bodily removed from the said batten, without any relative movement of the said dents with respect to each other.

In testimony, that I claim the foregoing as my invention, I have signed my name in presence of two subscribing witnesses.

GEORG MAX WEHNER.
